United States Patent Office

Des. 187,078

Patented Jan. 19, 1960

187,078

PLATE

Robert F. Williams, North Hollywood, Calif., assignor to Reynolds Metals Company, Richmond, Va., a corporation of Delaware

Application October 20, 1958, Serial No. 53,043

Term of patent 14 years

(Cl. D44—15)

FIG. 1

I claim:

The ornamental design for a plate, substantially as shown.
